(57) **CLAIM**

The ornamental design for a modular security drone payload, as shown and described.

DESCRIPTION

FIG. 1 is a front elevation view of the modular security drone payload;

FIG. 2 is a right side elevation view of the modular security drone payload of FIG. 1;

FIG. 3 is a rear elevation view of the modular security drone payload of FIG. 1;

FIG. 4 is a left side elevation view of the modular security drone payload of FIG. 1;

FIG. 5 is a top view of the modular security drone payload of FIG. 1;

FIG. 6 is a bottom view of the modular security drone payload of FIG. 1;

FIG. 7 is a front right upper perspective view of the modular security drone payload of FIG. 1;

FIG. 8 is a rear left upper perspective view of the modular security drone payload of FIG. 1;

FIG. 9 is a lower left perspective view of the modular security drone payload of FIG. 1; and,

FIG. 10 is a rear right perspective view of the modular security drone payload of FIG. 1.

The broken lines show features of the modular security drone payload that form no part of the claimed design.
